UNITED STATES PATENT OFFICE.

WILLIAM H. HOPE, OF PROVIDENCE, RHODE ISLAND.

PANTOGRAPH ENGRAVING-MACHINE.

1,219,311.

Specification of Letters Patent. Patented Mar. 13, 1917.

Application filed July 22, 1916. Serial No. 110,703.

To all whom it may concern:

Be it known that I, WILLIAM H. HOPE, a citizen of the United States, residing at Providence, in the county of Providence and State of Rhode Island, have invented a new and useful Improvement in Pantograph Engraving-Machines, of which the following is a specification.

This invention relates to certain new and useful improvements in a pantograph engraving machine and especially to a machine for engraving designs or patterns on cylindrical surfaces, as for instance, the large rolls used in printing rugs or carpet runners. These rolls, running from four to seven or more feet, in diameter, are so extremely heavy that the ordinary pantograph cannot well be employed owing to the fact that, in the ordinary pantograph, the roll 10 has a connection with the platen table which causes it to be rotated upon a movement of the stylus.

The primary object of the present invention, therefore, is to provide a machine 25 which will overcome these defects and will be thoroughly efficient in operation.

A further aim of the invention is to provide a pantograph engraving machine in which the stylus and cutting point are supported for movement about the roll.

Another object resides in the provision of a machine of the above type in which more than one operative can work thereon at the same time to thereby facilitate and expedite 30 the engraving operation.

The invention further resides in the salient features of construction and the arrangements and combinations of parts hereinafter described and claimed, the preferred embodiment of the invention being illustrated 40 in the accompanying drawings wherein—

Figure 1 is an end elevation of the improved pantograph engraving machine, parts of the frame being omitted.

Fig. 2 shows the machine in side or front elevation, and

Fig. 3 is a detailed perspective of a lever employed in the mechanism for lifting the cutting points from the work.

The numeral 1 designates the frame having a horizontal platform 2 from which rises a pair of uprights 3 having roller bearings 4 at their upper ends.

The metal roll 5, which is coated with varnish, has trunnions 6 journaled in the roller bearings 4, and fixed on the projecting end

of one trunnion is a spacing wheel 7 having a peripheral series of predeterminedly spaced apertures 8 in which a catch or stop 9, on the adjacent upright 3, is adapted to 60 selectively engage for holding the roll 5 fixed.

Spaced outwardly from the uprights 3 are the frame standards 10 to the opposite sides of which and concentric with the roll, are 65 pivoted the arms of inverted U-frames 11 which are counterbalanced by weights 12. On each frame 11 is supported a graver carriage 13 for movement longitudinally of the roll, and on said carriage is pivoted at 14 one 70 or more cutting points 15. It is obvious that the cutting points are mounted so as to move in any direction over the cylindrical surface of the roll 5, the counterbalanced frames 11 facilitating the circumferential movements 75 of the cutters without interfering with the longitudinal movements.

The design or pattern plates 16 are mounted on supports 17 extending upwardly from the platform 2 in arcs concentric with the 80 roll 5. Each carriage 13 is operated through the medium of an angular frame 18 which carries on its outer or lower end a stylus 19 for following the design on plate 16. Therefore, as the stylus traces the particular design on plate 16, the frame 18 will impart 85 the movements to the graver carriage for moving the same across the roll or up and down on the circumference thereof.

A wire 20, or other connection, joins each 90 pivoted cutter 15 to the arm 21 of a bell-crank lever 22, journaled in a frame 18, whereby, on depressing the arm 23 of the lever 22, the cutting point may be elevated 95 from the roll.

In practice, an operative on each side of the machine can copy his particular design from plate 16 onto the roll, and subsequent to this transferring operation by each operative, new design plates are substituted for 100 the ones just copied and the roll rotated sufficiently to present new surfaces beneath the cutting points, this operation being continued until the entire roll surface has been finished.

The circumference of the roll is intended to receive a complete number of transfers from the design plate so that as each plate represents a division of the completed design so might the circumference be said to have a 110 corresponding number of divisions.

The apertures 8 of the spacing wheel cor-

respond in number to the divisions of the completed design whereby, as each design section is copied and the roll rotated, the latch 9 will arrest the roll at the proper point to present a new division of the roll circumference. Consequently, after all of the divisions have been engraved by the cutting points, the complete design will be formed on the circumference of the roll.

10. Thus, the engraving is expeditiously carried on and, since the movements of the carriages are free, an efficient operation is readily afforded.

Having thus described my invention, 15 what I claim as new and desire to secure by Letters Patent is—

1. In a pantograph engraving machine, a frame having bearings for a roll to be engraved, a graver carriage mounted on the 20 frame for movement about the roll, a cutter pivoted to the carriage for cutting the roll, a support arranged concentric with the roll for supporting a design pattern, a second frame connected with the carriage, a 25 stylus on the second frame for following a pattern on the support, and means on the second frame connected to the pivoted cutter for raising and lowering the latter from and onto the roll.

30. 2. In a pantograph engraving machine, a frame having bearings for a roll to be engraved, a U-frame pivoted to the first frame for movement about the roll concentric therewith, a graver carriage supported on 35 the U-frame for movement over the circumference of the roll longitudinally of the latter, a cutting point on the carriage, a design pattern support, and a stylus connected to the carriage and arranged for following a 40 pattern on the support.

3. In a pantograph engraving machine, means for supporting a roll to be engraved, a graver carriage movable relative and concentric to the roll to be engraved, a cutter 45 on the carriage for cutting a design on the roll, a design pattern support, and a stylus connected with the carriage for following a pattern on the support and means for supporting the graver carriage.

50. 4. In a pantograph engraving machine, means for supporting a roll to be engraved, a graver carriage, means for holding the roll fixed, a cutter pivoted to the carriage for cutting the roll, a support arranged concentric with the roll for supporting a design pattern, a frame connected with the carriage, a stylus on the frame for following a pattern on the support, means on the frame connected to the pivoted cutter for raising and lowering the latter from and onto the roll and means for supporting the graver carriage.

55. 5. In a pantograph engraving machine, means for supporting a roll to be engraved, a graver carriage, means supporting the car-

riage for concentric and longitudinal movement relative to the roll, a cutter on the carriage, a stylus connected with the carriage and a support concentric with the roll for holding a pattern to be followed by the stylus.

6. In a pantograph engraving machine, a frame having bearings for a roll to be engraved, a counterbalanced U-frame pivoted to the first frame for movement about the roll concentric therewith, a graver carriage supported on the U-frame for movement over the circumference of the roll longitudinally of the latter, a cutting point on the carriage, a design pattern support, and a stylus connected to the carriage and arranged for following a pattern on the support.

7. In a machine of the character described, means for supporting a roll to be engraved, a plurality of U-frames having their arms extending radially of the roll and pivoted concentric thereto on said frame, a graver carriage mounted on each U-frame for movement longitudinally of the roll, a cutter on each carriage, and a stylus connected to each carriage.

8. In a machine of the character described, means for supporting a roll to be engraved, a plurality of U-frames having their arms extending radially of the roll and pivoted concentric thereto on said frame, counterbalance means for the carriages, a carriage movable on each U-frame longitudinally of the roll, a cutter on each carriage, a design pattern support, and a stylus connected to each carriage and arranged for following a pattern on the support.

9. In a machine of the class described, means for supporting a roll to be engraved, a graver carriage mounted on a supporting U-frame for movement concentric with and longitudinally of the roll, a cutter on the carriage, a support for holding one section at a time of the design pattern to be produced, a stylus for following the pattern connected to the carriage, and means for holding the roll fixed at predetermined points corresponding to the number of pattern sections whereby when all the pattern sections are finished a completed design will be obtained on the roll.

10. In a pantograph engraving machine, means for supporting a roll to be engraved, a graver carriage, means for supporting the carriage for concentric and longitudinal movement relative to the roll, a cutter pivoted on the carriage, a stylus connected with the latter, a lever pivoted adjacent the stylus, and a connection between the lever and pivoted cutter whereby the latter may be raised from the roll.

11. In a machine of the class described, means for supporting a roll to be engraved,

- a graver carriage mounted upon a U-frame for movement concentric with and longitudinally of the roll, a cutter on the carriage, a support for holding one section at a time of the design pattern to be produced, a stylus for following the pattern connected to the carriage, and a spacing wheel fixed with respect to the roll for rotating the roll to correspond to the pattern sections.
- 5 12. In a pantograph engraving machine, a frame, a counterbalanced U-frame pivoted to the first frame, a graver carriage movably mounted on the U-frame, a cutter pivoted to the carriage, a stylus-frame connected with the carriage, a stylus on the last frame, and means on the stylus frame connected to the pivoted cutter for raising and lowering the cutter.
- 10 13. In a pantograph engraving machine, a frame having roll bearings, a counterbalanced U-frame pivoted to the first frame, a graver carriage movably mounted on the U-frame, a cutter pivoted to the carriage, a stylus-frame connected with the carriage, a stylus on the last frame, a pattern support arranged adjacent the stylus and con-
- 15 centric with the roll bearings, and means on the stylus-frame connected to the pivoted cutter for raising and lowering the cutter. 30
14. In a pantograph engraving machine, a frame having bearings for the roll, means for holding the roll fixed on the frame, a graver carriage mounted on a counterbalanced U-frame concentric with the roll and 35 for movement about the latter, a cutter pivoted to the carriage for cutting the roll, a support arranged concentric with the roll for supporting a design pattern, a frame connected with the carriage, a stylus on the second frame for following a pattern on the support, and means on the stylus frame connected to the pivoted cutter for raising and lowering the cutter from and onto the roll. 40
- 15 In testimony whereof I have signed my 45 name to this specification in the presence of two subscribing witnesses.
